INGOT MOLD EXTRACTOR
Walter D. Maring, Shelby, Ind.
Filed Mar. 23, 1959, Ser. No. 801,022
12 Claims. (Cl. 22—95)

This invention relates to a new and improved machine or device for extracting a metal ingot or the like from a mold.

One object of the present invention is to provide a new and improved ingot mold extractor which is constructed so that the ingot is knocked loose from the mold by a blow from a heavy hammer which strikes the top of the ingot while the mold is being supported by the extractor.

A further object is to provide a new and improved device of the foregoing character in which one or more springs are employed to add considerable impetus to the downward movement of the hammer.

Another object is to provide such a new and improved ingot extractor which may easily be manipulated by an ordinary crane, the lifting force of the crane being employed to operate the extractor.

It is a further object to provide a new and improved extractor of the foregoing character in which the lifting force of the crane is employed to raise the hammer and to compress the springs, and in which the hammer is released, after a predetermined amount of upward movement, for downward movement under the force of the springs and the force of gravity.

Another object is to provide such an extractor in which the lifting effort of the crane is transferred to the mold after the hammer has been released.

A further object is to provide such an extractor which is arranged in a new and improved manner so that the extractor may readily be connected to and disconnected from the mold.

Still another object is to provide a new and improved extractor which is extremely effective and easy to manipulate, yet is remarkably low in cost.

Further objects and advantages of the present invention will appear from the following description, taken with the accompanying drawings, in which:

FIGS. 1, 2, and 3 are elevational section views of an ingot mold extractor to be described as an illustrative embodiment of the invention, the extractor being shown in three different stages of its operating cycle in the three views.

FIGS. 4, 5, and 6 are elevational views corresponding to FIGS. 1, 2, and 3, but taken at right angles thereto.

It will be seen that the drawings illustrate a device or machine 10 adapted to remove or strip a mold 12 from the upper portion 14 of a metal ingot 16 or the like. The illustrated mold 12 is actually the removable upper portion of a main or lower mold 18. The upper mold 12 is commonly known as a hot top mold, and the upper portion 14 of the ingot is commonly known as the hot top.

It will be seen that the molds 12 and 18 have downwardly tapering inner surfaces 20 and 22, so that the molds may be stripped upwardly from the ingot 16. The hot top mold 12 is formed with a pair of laterally projecting lugs 24, so that the mold may be grasped and lifted. Lifting lugs 26 are also formed on the main mold 18.

Despite the tapering of the molds 12 and 18, a great deal of force is required to extract or strip the molds from the ingot, if the extracting is done by the exertion of a steady force, as by a hydraulic press or the like. The illustrated extractor 10 is arranged to separate the mold 12 from the ingot hot top 14 by the shock of a

2

sharp, heavy blow applied to the top of the ingot while lifting force is being applied to the hot top mold. After the hot top mold 12 has been removed from the hot top 14, the main mold 18 may be removed from the ingot 16 by an extractor of the same design and mechanism but of larger size.

The illustrated extractor 10 is adapted to be operated and manipulated by an ordinary crane or other similar hoist, which is not shown, except for its lifting hook 28, shown in broken lines. The hook 28 is adapted to be connected to a bar or member 30 which is formed into an eye or loop. It will be seen that the eye member 30 extends upwardly from a first or upper frame 32, which may be fabricated from various steel members. To reduce the shock that may be caused when the extractor is lifted abruptly by the crane, the eye member 30 is preferably connected to the upper end of a bar or rod 34 which is slidable vertically to some extent, relative to the frame 32. A shock absorbing coil spring 36 is compressed between a slide block 38, secured to the lower end of the bar 34, and a stop block 40, mounted on the upper portion of the frame 32. The spring 36 is pre-loaded to a substantial extent. When the extractor 10 is lifted, the spring 36 will be further compressed to some extent. Of course, the spring 36 is made strong enough to sustain the weight of the extractor and the load placed thereon during the operation of the extractor.

In order to provide for the lifting of the hot top mold 12, the extractor 10 is formed with a second frame 44, the first frame 32 being movable vertically relative to such second frame 44. The second frame 44 may also be fabricated from various steel members or castings. It will be seen that the second frame is disposed below the first frame 32.

To grasp and lift the hot top mold 12, the second or lower frame 44 is fitted with a pair of depending arms 46 which are swingably mounted on the frame 44 by means of pivots 48. The lower end of each arm 46 is provided with a loop or eye member 50 which is adapted to move under one of the lifting lugs 24 on the hot top mold 12.

It will be apparent from a comparison of FIGS. 4 and 5 that the arms 46 are swingable inwardly and outwardly, into and out of lifting relation to the lugs 24. In FIG. 4, the arms are shown in their outwardly swung position, while in FIGS. 5 and 6 they are shown swung inwardly to embrace the lugs 24. A mechanism 54 is mounted on the lower frame 44 to swing the lifting arms 46 inwardly and outwardly. It will be seen that the mechanism 54 comprises pairs of similar components, one component of each pair being disposed on each side of the frame 44 to operate one of the arms 46. Thus, an operating arm 56 is mounted on each side of the frame 44 to push the corresponding arm 46 outwardly. In the illustrated construction, each arm 56 is secured to a shaft 58 which is rotatably mounted on brackets 60 secured to the frame 44. A roller 62 is preferably mounted on the outer end of the arm 56 to engage the arm 46. It will be apparent that each arm 46 has a curved upper portion 64 for engagement by the roller 62. When the arm 46 is fully swung outwardly, the operating arm 56 extends radially or at right angles to the upper portion 64 of the arm, so that the operating arm 56 is at a neutral or dead center position. This is clearly shown in FIG. 4. Thus, the weight of the arms 46 does not tend to change the positions of the operating arms 56. To assist in retaining the operating arms 56 in this position, the upper portions 64 of the arms 46 are formed with shallow notches or grooves 66 adapted to receive and retain the rollers 62.

The operating mechanism 54 comprises a linkage where-

by the operating arms 56 are connected together for simultaneous movement. Thus, an arm 68 is secured to each shaft 58. An adjustable link 70 extends between the arm 68 and an arm 72 secured to a shaft 74. It will be seen that the shafts 74 are fitted with meshing gears 78, so as to couple the shafts for simultaneous rotation in opposite directions.

In this case, the mechanism 54 is adapted to be operated by a lever 80 which is secured to the right hand shaft 74. The lever 80 may be pulled upwardly by means of a cable 82, connected to the outer end of the lever. A pull may be exerted on the cable 82 by any suitable means, such as a winch or solenoid on the crane which is employed to lift the ingot extractor 10. When the cable 82 is pulled upwardly, the operating arms 56 are swung outwardly to the positions shown in FIG. 4. The arms 56 push the lifting arms 46 outwardly, so that they will be disengaged from the lifting lugs 24 on the hot top mold 12. The outward movement of the arms 56 is limited by the engagement of the right hand arm 72 with an adjustable stop 84 on the left hand arm 72. In an emergency, the mechanism 54 may be operated by a hand lever 85, secured to the left hand shaft 74.

As already indicated, the operating arms 56 are detained in their outwardly swung positions by the reception of the rollers 62 in the grooves or notches 66. Additional means are provided to operate the mechanism 54 so as to swing the operating arms inwardly. This is accomplished in a highly advantageous manner by providing a bar 88 which is adapted to strike the top of the hot top mold 12 when the ingot extractor 10 is lowered. The engagement of the bar 88 with the mold 12 arrests the downward movement of the bar. However, the lowering movement of the extractor 10 is continued, so that there is relative movement between the bar 88 and the lower frame 44. This relative movement is employed to operate the arms 56 so as to permit the lifting arms 46 to swing inwardly by their own weight.

It will be apparent from FIG. 1 that the bar 88 extends in a horizontal direction from the lower end of a rod 90. Brackets 92 are provided on the lower frame 44 to guide the bar 90 for vertical movement relative to the frame. Of course, the bar 90 tends to move downwardly by its own weight. Downward movement of the bar 90 is limited by a washer or other shoulder member 94 which is mounted on the upper end of the bar and is engageable with the top of the uppermost bracket 92. At its upper end, the bar 90 is fitted with an adjustable screw 96 which is engageable with an arm 98 secured to the right hand shaft 74. When the bar 88 strikes the top of the hot top mold 12, the screw 96 pushes the arm 98 upwardly and thus swings the right hand shaft 74 clockwise. This disengages the rollers 62 from the grooves 66, whereupon the lifting arms 46 swing inwardly by their own weight, the eye members 50 embracing and engaging lugs 24.

To carry a portion of the initial load of bars 88 and 90, a coil spring 100 is mounted around bar 90 between the brackets 92, a stop collar 102 being provided to determine the portion of the load carried by the spring 100.

As already indicated, the mold 12 is stripped from the ingot by delivering a sharp blow against the top of the ingot. To deliver the blow, the ingot extractor 10 is provided with a large, heavy hammer 106 which is movable vertically relative to the upper and lower frames 32 and 44. It will be seen that the hammer 106 is positioned below the upper frame 32 and within guide channels 107 on the lower frame 44.

The hammer 106 is also guided for vertical movement by a plurality of guide rods 108. The illustrated construction employs four of the guide rods, although any suitable number may be utilized. It will be seen that the lower end of each rod 108 is secured to the hammer 106. The rods 108 extend upwardly from the hammer through an apertured guide member 110 on the upper end of the lower frame 44. The rods 108 then extend

upwardly through an apertured guide member 112 on the lower end of the upper frame 32. To limit downward movement of the rods 108, their upper ends are fitted with nuts 114 or the like. Short cushion springs 116 are mounted on the rods 108 above the upper guide member 112. These springs 116 are slideable along the rods and are adapted to engage the nuts 114 when the rods are moved downwardly to the maximum possible extent, as shown in FIG. 3. The springs 116 support the weight of the hammer 106 when it is in its lowermost position relative to the frame 32.

Releasable means are provided on the upper frame 32 to lift the hammer 106. In this case, the releasable means comprise a pair of depending tongs 120 which are swingably mounted on the frame 32 by means of pivots 122. The tongs 120 are adapted to swing inwardly and outwardly in and out of engagement with the hammer 106.

The lower end of each of the tongs 120 is formed with an inwardly directed hook 124 for lifting the hammer 106. In this case, each hook 124 is movable by its own unbalanced weight under a roller 126 mounted on the hammer. The rollers are positioned in recesses 128 formed on the opposite sides of the hammer 106. The provision of the rollers 126 facilitates the disengagement of the tongs 120 from the hammer 106.

As will be described in detail shortly the hammer 106 is dropped against the top of the ingot when the hammer is released by the tongs 120. Of course, the hammer is propelled downwardly by its own weight. To increase the downward acceleration of the hammer 106, the illustrated extractor 10 is provided with one or more springs 132. In the illustrated arrangement there are two of the springs 132, but it will be realized that a larger or a smaller number may be employed. The illustrated springs 132 are received around two of the rods 108, between the hammer 106 and the guide member 110 at the upper end of the lower frame 44. The springs 132 are of the coil compression type. In order to increase the permissible length of the springs 132, sockets 134 are formed in the hammer 106 to receive the lower portions of the springs.

When the hammer 106 is lifted by the tongs 120, the springs 132 are compressed between the hammer and the member 110, as clearly shown in FIG. 2. At this point in the cycle of operation, the lifting arms 46 are hooked onto the mold 12, so that the frame 44 is kept from moving upwardly by the weight of the mold and the ingot.

Means are provided to release the tongs 120 from the hammer 106 after the hammer has been raised to a position just below the top member 110 on the frame 44. For this purpose, the illustrated tongs 120 are formed with inwardly directed cams or projections 138, which are engageable with rollers 140 mounted on the top member 110 of the frame 44. As the tongs 120 are raised beyond the position shown in FIG. 2, the rollers 140 push the projections 138 outwardly, and thereby disengage the hooks 124 from the rollers 126. The tongs 120 are thrown outwardly beyond the hammer 106 so that it is released for downward movement under the force of gravity and the force of the springs 132. The springs rapidly accelerate the hammer so that it strikes a hard blow against the top of the ingot 16.

Until the hammer 106 moves downwardly, the lower frame 44 is supported by the springs 132. When the tongs 120 are moved outwardly, they hook onto the frame 44 and exert upward force thereon. To achieve this, each of the tongs 120 is formed with an outer hook 144 adapted to move under a hook receiving bar 146 at the top of the frame 44. Each hook 144 swings under the corresponding bar 146 before the inner hook 124 is fully disengaged from the hammer 106. The hooks 144 and the bars 146 are formed with complementary inclined surfaces 148 and 150. As the rollers 140 push the cams 138 outwardly, the inclined surfaces 148 on the hooks metallically engage the inclined surfaces 150 and slide outwardly and

upwardly therealong. The inclination of the surfaces 148 and 150 holds the tongs outwardly after the hammer 106 has been released.

Summary of Operation

It will now be of interest to trace the cycle of operation of the ingot extractor 10. FIGS. 1, 2 and 3 illustrate three stages in the operation of the extractor. The same three stages are also shown in FIGS. 4, 5 and 6, which are taken at right angles to FIGS. 1, 2 and 3. Actually, it will be convenient to begin the description of the cycle by referring to FIGS. 3 and 6, which show the final stage in the cycle. In these views, the hammer or striking assembly 106 is in its lowermost position, relative to the upper frame or control assembly 32. The hammer 106 is suspended in this position by the rods 108, which in turn are supported by the cushion springs 116. The lower frame or main body assembly 44 is suspended on the outer hooks 144 of the tongs 120. It will be seen that the hot top mold 12 has been separated or stripped from the hot top 14 of the ingot 16. The hot top mold 12 is hanging from the lifting arms 46.

In order to prepare the mold extractor 10 for another extracting cycle, the hot top mold 12 is lifted clear of the ingot hot top 14 and is lowered onto a storage stool, not shown. To release the arms 46 from the hot top mold 12, the cable 82 is pulled upwardly by a winch, solenoid or other motion work on the crane. This swings the lever 80 and the right hand shaft 74 counterclockwise. The meshing gears 78 cause the left hand shaft 74 to rotate clockwise. The rotation of the shafts 74 causes the arms 72 to swing inwardly toward each other. By virtue of the links 70 and the arms 68, the operating arms 56 are swung outwardly. The rollers 62 engage the arms 46 and push them outwardly, to the position shown in FIG. 4. As the arms 56 reach their dead center positions, the rollers 62 enter the detaining grooves 66. The arms 56 are thus retained in their outwardly swung positions so that the operating mechanism will not collapse under the weight of the lifting arms 46.

Next, the extractor 10 is lifted and moved by the crane over another mold 12 which is to be stripped from its ingot 16. The extractor 10 is lowered so that the lower end of the hammer 106 engages the upper edge of the hot top mold 12. Of course, the mold arrests the downward movement of the hammer 106. The extractor is lowered an additional amount so as to move the frames 32 and 44 downwardly relative to the hammer 106. The purpose of this operation is to re-engage the hammer 106 with the tongs 120. The top of the hammer engages the lower ends of the tongs 120 and swings them outwardly so that they will pass downwardly along the hammer and swing under the rollers 126. Bevelled or inclined surfaces 160 are formed on the upper end of the hammer 106 to swing the tongs 120 outwardly. The tongs swing inwardly by their own weight when they move beneath the rollers 126.

The extractor 10 is then lifted slightly so that the hammer 106 will clear the top of the hot top mold 12. Next, the extractor is repositioned slightly, so that the hammer 106 will be centered over the top of the ingot 16. The extractor is lowered so that the loops 50 on the lower ends of the arms 46 will be opposite the lifting lugs 24 on the mold 12, as shown in FIGS. 1 and 4. Further lowering movement of the extractor will cause the trip bar 88 to strike the top of the mold 12. As the frame 44 moves downwardly, the assembly comprising the bars 88 and 90 pushes the arm 98 upwardly. This rotates the right hand shaft 74 clockwise, so as to initiate downward swinging movement of the operating arms 56. Once the rollers 62 are disengaged from the grooves 66, the weight of the lifting arms 46 pushes the arms 56 downwardly, so that the arms 46 swing inwardly under the lugs 24.

Next, the crane is operated so as to lift the hook 28 and the upper frame 32. This also raises the tongs 120,

which, in turn, raise the hammer 106 as shown in FIGS. 2 and 5. The springs 132 are compressed as the hammer 106 is raised. It will be understood that the springs 132 push the lower frame 44 upwardly, but the lower frame is prevented from moving upwardly because the lifting arms 46 are hooked onto the mold 12.

As the hammer approaches the top member 110 of the frame 44, the tongs 120 are swung outwardly by the engagement of the cams 138 with the rollers 140. This moves the hooks 124 out from under the rollers 126, which also throw the tongs outwardly as the hammer 106 starts its descent. The hammer is accelerated downwardly by the force of gravity, greatly aided by the force of the springs 132. Thus, the hammer strikes an extremely hard blow against the top of the hot top portion 14 on the ingot 16. The shock of the blow loosens the ingot from the hot top mold 12.

During the critical period in which the tongs 120 swing outwardly and thus release the hammer 106, the outer hooks 144, move under the bars 146 on the frame 44, bringing the mating inclined surfaces 148 and 150 into metallic engagement, so that the frame is caught and supported by the tongs during and after the descent of the hammer. At this stage the crane has the complete unit stressed up, through frame 32, tongs 120, second frame 44, and lifting arms 46, which are attached to ears 24 of mold 12. Thus, the hot top mold 12 is pulled upwardly as the crane rises. As shown in FIG. 3, the hot top mold 12 and the hammer 106 are lifted clear of the ingot hot top 14.

The extractor may readily be operated and manipulated with an ordinary crane. No unusual lifting effort is imposed upon the crane. The operating cycle of the extractor may be completed very quickly so that the extractor will be able to strip a great many molds in a minimum period of time. It will be apparent that the extractor is rugged and effective, yet is remarkably low in cost. The extractor may be made in various sizes and types, to strip various types and sizes of molds from metal ingots or the like.

I am well acquainted with the following U.S. patents relating to the general field of ingot mold extractors:

Inventor	Patent No.

Various other modifications, equivalents and alternative constructions may be employed without departing from the true spirit and scope of the invention, as exemplified in the foregoing description and defined in the following claims.

I claim:

1. In a device for extracting an ingot from a mold having lug engaging means thereon, the combination comprising a main frame, a hammer slidably mounted to said main frame to be raised and projected downward upon an ingot, a hammer lifting frame slidably mounted to said main frame for raising and releasing said hammer, said lifting frame including lifting tongs pivotally mounted to automatically engage and raise said hammer within the confines of said main frame, means for lowering said device for initially engaging said hammer against an

ingot to urge said hammer partially upward into engagement with said tongs, compression springs mounted to said main frame and confronting said hammer for biasing said hammer downward when raised by said lifting means relative to the main frame, arm means mounted to said main frame for anchoring said main frame relative to a mold when said hammer is raised by said lifting means, means on said arms to releasably engage said mold, cam means on said main frame automatically engaging and camming said tongs outward when said hammer reaches its raised position to release said hammer from said tongs whereby said hammer may be projected downward against an ingot with its movement accelerated by said biasing action of said compression springs.

2. In a device according to claim 1, wherein said lifting tongs include tapered outward and upward diverging finger portions, and said main frame includes tapered edge portions whereby when said tongs are cammed outward said finger portions will engage said tapered edges of said main frame to suspend said main frame relative to the mold.

3. In a machine for extracting an ingot from a tapered mold of the type having laterally projecting lifting lugs thereon, the combination comprising a first frame adapted to be lifted by a lifting means, means on said first frame for coupling with said lifting means, a second frame having a pair of depending lifting arms pivotally mounted thereon and receivable under the lifting lugs on the mold, said first frame being relatively movable vertically with respect to said second frame, means on said second frame for swinging said arms inwardly and outwardly into and out of engagement with the lifting lugs on the mold, a hammer movable vertically relative to said first and second frames, guide means providing for relative vertical movement of said first frame, said second frame and said hammer while preventing any substantial relative lateral movement thereof, a pair of tongs pivoted on said first frame and releasably engageable with said hammer for lifting said hammer in response to lifting movement of said first frame by the lifting means, spring means disposed between said hammer and said second frame and adapted to be compressed by upward movement of said hammer relative to said second frame, and means for releasing said tongs from said hammer after predetermined upward movement of said first frame relative to said second frame, said hammer thereby being released for downward movement under the force of said spring means and the force of gravity, said tongs having means movable therewith into supporting relation to said second frame when said tongs are released from said hammer.

4. In a device for extracting an ingot from a mold, the combination comprising a first frame adapted to be lifted by a lifting means, a second frame having releasable means thereon for grasping and lifting the mold, said first frame being relatively movable vertically with respect to said second frame, a hammer movable vertically relative to said first and second frames, guide means interconnecting said first frame, said second frame and said hammer for relative vertical movement, spring means disposed between said second frame and said hammer and adapted to be stressed by upward movement of said hammer relative to said second frame, releasable means on said first frame for lifting said hammer in response to lifting movement of said first frame by the lifting means, and means for releasing said last-mentioned releasable means from said hammer in response to a predetermined amount of upward movement of said first frame relative to said second frame, said hammer thereby being released for downward movement against the ingot under the force of said spring means and the force of gravity.

5. In a device for extracting an ingot from a mold, the combination comprising a first frame adapted to be lifted by a lifting means, a second frame having releasable means thereon for grasping and lifting the mold, a hammer movable vertically relative to said first and second

frames, guide means interconnecting said first frame, said second frame and said hammer for relative vertical movement, spring means disposed between said second frame and said hammer and adapted to be compressed by upward movement of said hammer relative to said second frame, releasable means on said first frame for releasably grasping said hammer to lift said hammer in response to lifting movement of said first frame by the lifting means, and means for releasing said last-mentioned releasable means from said hammer in response to a predetermined amount of upward movement of said first frame relative to said second frame, said hammer thereby being released for downward movement against the ingot under the combined forces of gravity and said spring means.

6. In a machine for extracting an ingot from a tapered mold of the type having laterally projecting lifting lugs thereon, the combination comprising a first frame adapted to be lifted by a lifting means, means on said first frame for coupling to said lifting means, a second frame having a pair of depending lifting arms pivotally mounted thereon and receivable under the lifting lugs on the mold, means on said second frame for swinging said arms outwardly out of engagement with the lifting lugs on the mold, means operable by engagement with the mold for swinging said arms inwardly into engagement with the lugs, a hammer movable vertically relative to said first and second frames, guide means providing for relative vertical movement of said first frame, said second frame and said hammer while preventing any substantial relative lateral movement thereof, a pair of tongs pivoted on said first frame and releasably engageable with said hammer for lifting said hammer in response to lifting movement of said first frame by the lifting means, spring means disposed between said hammer and said second frame and adapted to be stressed by upward movement of said hammer relative to said second frame, and means for releasing said tongs from said hammer after predetermined upward movement of said first frame relative to said second frame, said hammer thereby being released for downward movement under the force of said spring means and the force of gravity, said tongs having means movable therewith into supporting relation to said second frame when said tongs are released from said hammer.

7. In a machine for extracting an ingot from a tapered mold of the type having laterally projecting lifting lugs thereon, the combination comprising a first frame adapted to be lifted by a lifting means, means on said first frame for coupling with said lifting means, a second frame having a pair of depending lifting arms pivotally mounted thereon and receivable under the lifting lugs on the mold, means on said second frame for swinging said arms outwardly out of engagement with the lifting lugs on the mold, means operable by engagement with the mold for swinging said arms inwardly into engagement with the lugs, a hammer movable vertically relative to said first and second frames, guide means providing for relative vertical movement of said first frame, said second frame and said hammer while preventing any substantial relative lateral movement thereof, a pair of catches movable on said first frame and releasably engageable with said hammer for lifting said hammer in response to lifting movement of said first frame by the lifting means, spring means disposed between said hammer and said second frame and adapted to be stressed by upward movement of said hammer relative to said second frame, and means for releasing said catches from said hammer after predetermined upward movement of said first frame relative to said second frame, said hammer thereby being released for downward movement under the force of said spring means and the force of gravity, said catches having means movable therewith into supporting relation to said second frame when said catches are released from said hammer.

8. In a device for extracting an ingot from a mold, the combination comprising a first frame adapted to be lifted by lifting means, a second frame, movable vertically

relative to the first frame, releasable means on said second frame for grasping and lifting the mold, a hammer movable vertically relative to the first and second frames, guide means interconnecting said first frame, second frame and hammer, spring means on said guide means between said second frame and hammer and adapted to be stressed upon upward movement of the hammer relative to the second frame, releasable means on the first frame engageable with the hammer for lifting said hammer relative to the second frame and compressing the spring means when the first frame is lifted by said lifting means, means on the second frame for releasing said releasable means in response to a predetermined amount of upward movement of said first frame relative to the second frame whereby said hammer is freed for downward movement against the ingot under force of said spring means and the force of gravity.

9. The device described in claim 8 in which the second frame is below the first frame and the hammer is below the second frame.

10. The device described in claim 8 in which the guide means comprises rods on the hammer and extending up-

wardly through guide openings in the second and first frames.

5 11. The device described in claim 8, in which the releasable means engages with the second frame to hold it in elevated position when the hammer is released.

12. The device described in claim 8 in which the means for releasing the releasable means comprises cam means on the second frame and cam surfaces on the releasable means engageable by said cam means.
